UNITED STATES PATENT OFFICE

2,044,876

WAGON DRILL

John C. Curtis, Garfield Heights, Ohio, assignor
to The Cleveland Rock Drill Company, Cleve-
land, Ohio, a corporation of Ohio

Application March 15, 1933, Serial No. 660,884

18 Claims. (CL 255—51)

This invention relates broadly to rock drills, but more particularly to wagon drill of the drifter type.

Heretofore rock drills of this type were manufactured to comprise a vertical frame upon which the rock drill was slidably mounted. This frame was usually integrally mounted on a horizontal frame equipped with wheels for facilitating the moving of the assembly. To the vertical frame was affixed either a hand operated or fluid operated hoist, by which the rock drilling motor could be elevated on the frame to permit the removal of the drill steel from the drilled hole. During the drilling operation, the hoist was simply released to permit the downward travel of the rock drill, the feeding power of the latter being directly proportional to its weight. While drilling in rock of different density, difficulties were often encountered since no means were provided to retard or increase the feed of the machine according to the density of the rock being drilled. The vertical frame being integrally secured to the horizontal frame eliminated the possibility of drilling holes other than vertical, thus greatly reducing the application of such a machine.

One object of this invention is to produce a readily movable carriage for rock drill wherein the member upon which the rock drill is slidably mounted may be swung and secured into any desired position.

Another object of this invention is to produce a carriage for rock drill wherein the frame upon which the rock drill is slidably mounted, may be moved in such a manner as to permit the drilling of a plurality of parallel holes without necessitating the displacement of the carriage.

Another object of this invention is to produce a rock drill mounted on a wagon like supporting frame equipped with means for rigidly securing the same to the ground.

Another object of this invention is to produce a mounting for rock drill having all the characteristics of a wagon drill, but equipped with a mechanism capable to feed the rock drill toward and away from the work.

In the drawings which illustrate a preferred embodiment of the invention:

Fig. 1 is a plan view of the carriage assembly, illustrating the rock drill and its feeding mechanism located in a vertical position.

Fig. 2 is a cross sectional view taken in a plane indicated by line 2—2 in Fig. 1, with the rock drill located in the horizontal position.

Fig. 3 is a cross sectional view taken in a plane indicated by line 3—3 in Fig. 1.

Fig. 4 is an enlarged sectional view of the feeding mechanism shown in Fig. 3.

Fig. 5 is an enlarged view illustrating the clamping device of the feeding mechanism on the supporting frame.

Fig. 6 is a cross sectional view taken in a plane indicated by line 6—6 in Fig. 5.

Fig. 7 is a view illustrating the feeding mechanism together with the system of conduits pertaining thereto.

Fig. 8 is an enlarged sectional view of the throttle valve and pressure regulating valve illustrated in Fig. 7.

Fig. 9 is an enlarged cross sectional view taken in a plane indicated by line 9—9 in Fig. 7.

Referring to the drawings in which like characters designate corresponding parts throughout the several views, 10 represents the two side channel bars of a frame which are, toward the right end thereof, united by a cross member or handle 11. Welded on each of the channel bars 10, at a selected distance from the left end thereof, there is a transversely disposed bracket 12, being formed with an enlarged circular flange 13, disposed in the interior of the channel bars.

Extending from the center of the internal vertical face of each of the flanges 13, there is a stem 14 formed of differential diameters, the outer end portion thereof being threaded to receive a nut 15. The brackets 12 are also each provided with a shaft 16 extending to the exterior of the members 10, and capable of receiving a wheel 17.

The wheel may be secured thereon by any suitable means, as for instance by means of a pin 18, which is simply inserted into a vertical aperture disposed within the end portion of the shaft. The internal vertical face of the flange 13 is formed with a circular T-shaped groove 19, having slidably mounted therein the heads of two bolts 20. These bolts and heads may be introduced into the groove 19 through an aperture 21 leading from the opposite vertical wall of the flange into the groove. Located between the two side members 10, there is a substantially U-shaped tool supporting frame or yoke 22, comprising a tubular member 23 having welded thereto at each end thereof an arm 24. These arms are each formed with three transversely disposed apertures, the middle one thereof being adapted to receive the enlarged portion of the stem 14 upon which said arm is rotatably mounted. The other apertures are properly located to receive the bolts 20 which protrude from the groove 19. The bolts 20 are of sufficient length

to receive the nuts 25, by which the yoke 22 may be locked into any desired position.

On each side of the bracket 12, at selected distances therefrom, in the channel bars 10 are formed apertures 26. Disposed adjacent to these apertures, on the inner face of bars 10 are U-shaped plates 27 having the side walls thereof engaging the flanges of the channel bars 10. These plates are provided with apertures similar to the apertures 26, capable of receiving holders 28 which project interiorly of the frame. One end of each of these holders is formed with an enlarged head 29 abutting the plate 27. Formed through each of the holders 28, there is an elongated aperture 30 adapted to receive a frame supporting pin 31. The elongated aperture 30 is located in such a manner as to permit the engagement of the pin 31 with the base of the channel bars 10. Each of the holders 28 is properly machined to receive a set screw 32 capable of engagement with the pin 31 for locking the latter in any desired position in the holder 28. It will be observed that by loosening the screws 32, the pins 31 are free to slide within the elongated apertures 30, while the holders 28 together with the pins 31 are free to rotate with respect to the channel bars 10, thus permitting lineal as well as angular adjustment of the pins.

The frame supporting pins 31 mounted adjacent the left end of the frame in Fig. 1 are located closer to the wheels than the pins mounted on the right end portion of the frame. When it is desired to anchor the frame to the ground, it is desirable to elevate the wheels therefrom. This may readily be accomplished by first lowering the right end of the frame to the ground. Subsequently the pins mounted on the left end of the channel bars 10 may be lowered and secured in the frame in engagement with the ground. The operator may then apply lifting power on the handle 11 to move the frame into horizontal position. Subsequently the pins adjacent the handle 11 may then be lowered until they touch the ground and secured in such a position in the frame, thus rigidly securing the frame to the ground, with the wheels elevated therefrom.

Mounted on the substantially U-shaped frame on yoke 22, there is a feed tube 33, having affixed to the exterior thereof two parallel guides 34, upon which a rock drill 35 is free to slide. Disposed within the feed tube 33, there is a fluid actuated feeding mechanism including a piston 36 and chain 37, through which slidable movement is transmitted to the drill 35. Since the construction of this feeding mechanism is identical to the construction described in my United States Patent No. 2,029,223, no further description of the same is thought necessary.

Secured to the lower end of the feed tube 33, there is a front head 38, formed with a cylindrical portion 39 capable of engagement within the feed tube 33. The portion of the front head 38 protruding from the feed tube is elongated to extend laterally past the marginal edge of the feed tube, and has formed on the end face thereof a semi-circular groove 40 of a diameter equal to the diameter of the yoke tubular member 23, and adapted to engage the latter. Disposed on the four corners of the front head, there are provided apertured lugs 41 adapted to receive the bolts 42. Corresponding to the forward shape of the front head 38, there is a cap 43 formed with a groove 44 similar to the groove 40. This cap is also formed with apertured lugs 45 through

which the bolts 42 are free to pass to receive the nuts 46. Thus the feed tube assembly may be secured to the tubular member 23 of the yoke 22 by tightening the nuts 46. By loosening the nuts 46, the boom 33 may be swung into any desired position.

Secured to the upper end of the feed tube 33, there is a backhead 47 which is a replica of the front head 38. These two heads are secured to the feed tube by a pair of bolts 48 extending from one head to the other.

Affixed to one side of the feed tube 33, there is a motive fluid conveying conduit or pipe 49, equipped with a throttle valve 50, which is located at a convenient distance from the ground. The pipe 49 is connected to the rock drill 35 by a hose 51.

Adjacent the pipe 49, there is another pressure fluid conveying conduit 52, constantly admitting motive fluid into a throttle valve housing 53. In this housing is slidably mounted a throttle valve 54 operable by a handle 55 for controlling the admission and exhaust of the motive fluid into and from the feed tube 33, through inlet conduits 56 and 57, and outlet conduits 58 and 59. From the inlet conduit 57, the motive fluid is forced to flow through a pressure regulating valve 60 before it is finally admitted into the feed tube 33 through a conduit 61. Since the throttle valve 54 and the pressure controlling valve 60 form no part of the present invention, no further description is thought necessary.

Referring now to the carriage construction together with the means by which the feed tube is affixed to the yoke 22, it has been previously explained that the feed tube 33 may be rotated in a substantially vertical plane by simply loosening the nuts 46. Simultaneously the feed tube 33 may be moved laterally on the tubular member 23, thus it may be rotated in a plurality of parallel planes. When it is required to drill a series of vertical holes in parallelism with the yoke tubular member 23, the tube 33 may be positioned vertically on that member at a place adjacent to one of the arms 24. After the drilling of each hole, the tube 33 may be shifted laterally on the member 23, thus permitting the drilling of a plurality of holes on a line parallel to the member 23, without necessitating the constant displacement of the carriage. When it is desired to drill a plurality of horizontal holes on a vertical plane, the yoke 22 may first be lowered to the ground with the tube 33 secured horizontally thereon. After the drilling of each hole, the yoke 22 may be rotated upwardly by loosening the nuts 25 and the position of the tube 33 thereon corrected to a horizontal position, thus permitting the drilling of a plurality of horizontal holes in a vertical plane without necessitating the displacement of the carriage.

In excavation work, it is often necessary to drill vertical holes in immediate proximity of a vertical wall. This may be accomplished by swinging the yoke 22 into horizontal position away from the handle 11, and positioning the tube 33 vertically thereon (Fig. 7). The offset of the yoke 22 is such that the tube 33 may be located to permit the position of the rock drill in the immediate vicinity of the vertical wall without any interference from the left end of the channel bars 10.

When it is desired to drill upwardly in a substantial vertical direction, the tube 33 may be turned around to secure the engagement of the back head 47 with the yoke 22. Since the back

head 47 is a replica of the front head 38, the former is capable of receiving the bolts 42, and cap 43 for securing the tube 33 to the yoke 22. In this instance, when the tube 33 is placed vertically on the yoke 22, the rock drill is pointed upwardly, and may be fed in that direction as previously explained in connection with the forward or downward motion of the drill.

Although the foregoing description is necessarily of a detailed character, in order to completely set forth the invention, it is to be understood that the specific terminology is not intended to be restrictive or confining and it is to be further understood that various rearrangements of parts and modification of structural detail may be resorted to without departing from the scope or spirit of the invention as herein claimed.

I claim:

- 20 1. In a rock drill mounting, a supporting frame, a drill guiding frame having a drill slidably mounted thereon, each end portion of said drill guiding frame being the replica of the other end portion thereof, a substantially U-shaped member pivotally connected to said frames, and means including one of said end portions for establishing a rigid connection between said frames.
- 25 2. A rock drill mounting having a supporting frame, a substantially U-shaped member pivotally connected to said frame, a drill guiding frame, the end portions of said drill guiding frame being replicas of each other, a drill slidably mounted on said drill guiding frame, means including one of the end portions of said drill guiding frame for pivotally mounting said drill guiding frame on said U-shaped member, and means for locking the parts in their adjusted position to form a rigid connection between the drill guiding frame and the supporting frame.
- 30 3. In a portable drilling rig, the combination, of a carrying frame comprising a single unit, bearings carried by said frame, a substantially U-shaped tool supporting frame pivotally connected by said bearings to said carrying frame, and means forming a part of said bearings for holding said tool supporting frame in adjusted position.
- 35 4. In a portable drilling rig, the combination, of a carrying frame comprising a single unit, bearings carried by said frame, a substantially U-shaped tool supporting frame pivotally connected by said bearings to said carrying frame, and means forming a part of said bearings for holding said tool supporting frame in adjusted position.
- 40 5. In a portable drilling rig, the combination, of a carrying frame, supporting wheels carried by said frame, a substantially U-shaped tool supporting frame, means pivotally connecting said tool supporting frame to said carrying frame, said pivotally connecting means including means for holding said tool supporting frame in adjusted positions.
- 45 6. In a portable drilling rig, the combination, of a flat open ended carrying frame, supporting means for said frame, a U-shaped tool supporting frame having its ends pivotally connected to the carrying frame, the portion of the carrying frame between the pivotal axis of the supporting frame and one end being unobstructed to allow the sub-
- 50 7. In a portable drilling rig, the combination of a carrying frame having an open center, supporting means for said frame, a tool supporting frame pivotally connected to said carrying frame, a rock drilling mechanism supported by said supporting frame on an axis parallel to the pivotal axis of said supporting frame, one end of said drilling mechanism being capable of movement through the open center of the carrying frame, said drilling mechanism being adjustable longitudinally of said carrying frame by the pivotal movement of the supporting frame, and means for locking the two frames against relative movement.
- 55 8. In a portable drilling rig, the combination, of a flat open center carrying frame, supporting means for said frame, a substantially U-shaped tool supporting frame pivotally carried by said carrying frame, means for locking said frames against relative movement, and a rock drilling mechanism supported by the portion of said U-shaped supporting frame which is parallel to its pivotal axis whereby one end of the drilling mechanism is adjustable longitudinally and within the open portion of the carrying frame by the pivotal movement of said supporting frame.
- 60 9. In a portable drilling rig, a carrying frame having an open center portion, supporting means for said frame, a U-shaped tool supporting frame having its legs pivotally connected to the carrying frame, the space between the pivotal connections being unobstructed, said supporting frame being capable of adjustment from a horizontal position through a vertical position, and means to lock the frames against relative movement.
- 65 10. In a portable drilling rig, the combination, of a U-shaped carrying frame, supporting means for said carrying frame, a U-shaped tool supporting frame having its ends pivotally connected to the carrying frame, the portion of the carrying frame between the pivotal axis of the supporting frame and its open end being unobstructed to allow the U-shaped supporting frame to swing across the plane of the carrying frame, and means for locking the frames against relative movement.
- 70 11. In a portable drilling rig, the combination of a carrying frame including two side members, supporting wheels for said frame, means including a stationary element on each of said side members for rotatably mounting said wheels on said carrying frame, a substantially U-shaped tool supporting frame, means including said stationary element pivotally connecting said tool supporting frame to said carrying frame, said pivotally connecting means including means for holding said tool supporting frame in adjusted position.
- 75 12. In a portable drilling rig, the combination of a carrying frame, wheels rotatably supporting said frame, a substantially U-shaped tool supporting frame, means pivotally connecting said tool supporting frame to said carrying frame, the pivotal axis of said supporting frame being coaxial with the rotatable axis of the wheels, said pivotally connecting means including means for holding said tool supporting frame in adjusted position.
- 80 13. In a portable drilling rig, the combination of a carrying frame, supporting wheels carried by said frame, a substantially U-shaped tool supporting frame, means pivotally connecting said tool supporting frame to said carrying frame, and

means disposed on an axis parallel to the pivotal axis of said supporting frame for holding said supporting frame in adjusted position.

14. In a portable drilling rig, the combination 5 of a carrying frame, supporting wheels for said frame, anchoring means adjustably carried by said frame ahead of said wheels, a substantially U-shaped tool supporting frame, means pivotally connecting the legs of said supporting frame to 10 the carrying frame, said pivotally connecting means including means located between the legs for holding said supporting frame in adjusted position.

15. In a portable drilling rig, the combination 15 of a carrying frame including two side members united by a cross member, said cross member constituting a handle for said frame, supporting means for said frame, a leg adjustably carried by each of said side members, bearings carried by 20 said frame, a substantially U-shaped tool supporting frame pivotally connected by said bearings to said carrying frame, and means for locking the frames against relative movement.

16. In a portable drilling rig, the combination 25 of a flat open ended carrying frame, supporting means for said frame, a U-shaped tool supporting frame having its legs pivotally connected to the carrying frame, the portion of the carrying frame between the pivotal axis of the supporting frame 30 and one end being unobstructed to allow the tool supporting frame to swing across the plane of the

carrying frame, and means carried by the legs for rotation therewith for locking the frames against relative movement.

17. In a portable drilling rig, the combination 5 of a flat open ended carrying frame, supporting means for said frame, a substantially U-shaped tool supporting frame having its ends pivotally connected to the carrying frame, a drilling mechanism pivotally carried by said tool supporting frame, the portion of said carrying frame between 10 the pivotal axis of the supporting frame and one end being unobstructed, said drilling mechanism being adjustable longitudinally of said carrying frame with one end of the former being swingable through the unobstructed portion of said carrying 15 frame due to the pivotal movement of said U-shaped supporting frame, and means for locking said frames against relative movement.

18. In a portable drilling rig, the combination 20 of a carrying frame formed with an unobstructed open portion, supporting means for said frame, a tool guiding frame carried by said carrying frame, a connecting member between said frames pivotally connected to said frames, said tool guiding frame being adjustable longitudinally of said 25 carrying frame with one end of the former being allowed to swing through the unobstructed open portion of the latter due to the pivotal movement of said connecting member, and means for locking said frames against relative movement.

JOHN C. CURTIS.
